UNITED STATES PATENT OFFICE.

EMERY J. SCHANCK, OF CENTRALIA, WASHINGTON.

ENGINEER'S VALVE.

1,253,283.

Specification of Letters Patent. Patented Jan. 15, 1918.

Application filed April 29, 1916. Serial No. 94,440.

To all whom it may concern.

Be it known that I, EMERY J. SCHANCK, a citizen of the United States, residing at Centralia, in the county of Lewis and State of Washington, have invented certain new and useful Improvements in Engineers' Valves, of which the following is a specification.

My invention relates to improvements in engineers' brake valves.

An important object of the invention is to provide a brake valve of the above mentioned character, so constructed that the same may be manually operated to supply a desired degree of pressure to the brakes, and which automatically operates to retain such pressure constant for a prolonged period.

A further object of the invention is to provide a valve of the above mentioned character, which is simple in construction, inexpensive to manufacture, convenient in use, strong and durable.

Other objects and advantages of the invention will be apparent during the course of the following description.

In the accompanying drawings forming a part of this specification and in which like numerals are employed to designate like parts throughout the same,

Figure 1 is a central vertical longitudinal sectional view through apparatus embodying the invention,

Fig. 2 is a horizontal sectional view taken on line 2—2 of Fig. 1, and,

Fig. 3 is a section of a plurality of elements, separated and in the position to be assembled,

In the drawings, wherein for the purpose of illustration is shown a preferred embodiment of my invention, the numeral 5 designates a valve casing, the upper end of which is closed by a cap 6 having a gland 7, as shown.

The casing 5 is provided in its bottom with a pressure inlet coupling 8 having connection with the pressure supply pipe 9. Upon one side the casing 5 has an outlet coupling 10, having connection with a pressure outlet pipe 11, which leads to the brakes or train line. Connected with the opposite side of the casing 5 is a pipe 12, communicating with the pressure gage 13, which indicates the degree of pressure being applied to the brakes.

The gland 7 has a screw-threaded opening 14, receiving an exteriorly screw-threaded

tubular stem 15, the lower end of which is forked to provide spaced arms 16. These arms are adapted to fit between ears 17 rigidly mounted upon a rotatable exhaust valve 19, and preferably formed integral therewith. This exhaust valve has an exhaust port 20 formed therein, and adapted to be moved into and out of registration with an exhaust port 21 formed in the bottom of the casing 5. The exhaust valve 19 is rotatably mounted upon the bottom of the casing 5 and has a central opening 22, in permanent registration with the coupling 8. Rigidly attached to the upper end of the spindle 15 is a hand lever 23, adapted to contact with a stop 24, rigidly attached to the cap 6, when the pressure is cut off from the brakes and exhaust port 20 moved into registration with the exhaust port 21 whereby the interior of the casing 5 is placed in communication with the atmosphere. The numeral 25 designates a pressure control valve, which is vertically movable, arranged near and above the inlet coupling 8 and has an extension 26 operating therein. The valve 25 is provided with an opening or recess 27, which does not extend entirely therethrough and this recess receives the reduced end 28 of a coupling 29. The upper end 25 of this coupling fits within a compression coil spring 30, receiving the reduced lower end of a coupling 31. Fitting within a recess in the coupling 31 is a tension rod 32, extending through the tubular spindle 15 and having screw-threaded engagement therewith. The upper end of this rod is preferably formed square for engagement with a suitable tool for turning it and the tension rod carries lock nut 33, as is obvious.

In operation, the lever 23 is swung to the inactive or exhaust position, until it contacts with the stop 24. The exhaust port 20 is now in registration with the exhaust port 21. If pressure is fed into the casing 5 from coupling 8, the tension rod 32 is adjusted until the spring 30 is placed under compression to cut off this supply of pressure.

It may be assumed that there is a constant pressure of sixty pounds maintained in the pipe 9, and the spring 30 is normally tensioned or adjusted to overcome this pressure, while the exhaust valve 19 is in the exhaust position. In other words, the valve 25 is seated when the exhaust valve is in the exhaust position.

To apply the brakes, the lever 23 is swung to the right, and turns the exhaust valve 19 to the closed position. The turning movement of the stem 15 causes it to move upwardly, thereby reducing the compression of the spring 30, whereby the sixty pounds pressure in the pipe 9 will unseat the valve 25. This valve remains unseated until the pressure in the shell 5 is equal to the pressure in the pipe 9, there being then no tendency for pressure to pass through the opening of the valve seat, at which time the spring 30 will close the valve 25. The valve 25 automatically opens when the pressure is lowered in the shell 5, caused by the pressure leading from the brake cylinders or the like. It is thus apparent that the valve 25 does not prevent the maintaining of sixty pounds pressure in the brake cylinder, when the lever 23 is swung to the brake applying position.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. In an air brake valve of the character described, a casing provided in its bottom with a fluid pressure inlet opening and in its side with a fluid pressure outlet opening, said casing being also provided in its bottom with an exhaust opening which leads to the atmosphere, a rotatable disk valve arranged upon the bottom of the casing and having a substantially centrally arranged opening in permanent communication with the fluid pressure inlet opening and an exhaust opening adapted for movement into and out of registration with the first named exhaust opening, a rotatable spindle having screw-

threaded engagement with the top of the casing to move longitudinally when rotated, means to turn the spindle, a movable pressure inlet valve arranged within the casing adjacent its bottom and serving to close the fluid pressure inlet opening, and a spring contacting with the pressure inlet valve and connected with the spindle to have its tension regulated thereby. 50

2. In an air brake valve of the character described, a casing provided in its bottom with a fluid pressure inlet opening and in its upper portion with a fluid pressure outlet opening, said casing being also provided in its bottom with an exhaust opening which leads to the atmosphere, a rotatable disk valve arranged upon the bottom of the casing and having a substantially centrally arranged opening in permanent communication with the fluid pressure inlet opening and an exhaust opening adapted for movement into and out of registration with the first named exhaust opening, pairs of up-standing lugs formed upon the upper side 70 of the disk valve, a rotatable tubular spindle having screw-threaded engagement with the top of the casing to move longitudinally when rotated and provided at its lower end with a fork having tines fitting between the pairs of lugs, means to turn the spindle, a movable pressure inlet valve arranged within the casing adjacent its bottom and serving to normally close the pressure inlet opening, a spring engaging the pressure inlet valve, and a rod having screw-threaded engagement within the tubular spindle and connected with the spring. 60

In testimony whereof I affix my signature in presence of two witnesses.

EMERY J. SCHANCK.
